WALTER E. LOMBARD, OF ARLINGTON, MASSACHUSETTS, ASSIGNOR TO A. O. NORTON,
INC., OF BOSTON, MASSACHUSETTS, A CORPORATION OF MAINE.

RETARDING MECHANISM FOR LIFTING-JACKS.

1,383,221.

Specification of Letters Patent. Patented June 28, 1921.

Application filed August 3, 1920. Serial No. 401,069.

To all whom it may concern:

Be it known that I, WALTER E. LOMBARD, a citizen of the United States of America, and a resident of Arlington, in the county 5 of Middlesex and State of Massachusetts, have invented certain new and useful Improvements in Retarding Mechanism for Lifting-Jacks, of which the following is a specification.

10 This invention relates to retarding mechanism for high speed lifting jacks and has for its object the provision of means for preventing the jack lowering too rapidly.

The invention consists of providing the 15 worm shaft of a self-run-down lifting jack with a speed retarder connected thereto by a one-way driving connection whereby said retarder is rotated in one direction only and that during the lowering of the jack.

20 The invention further consists in mechanism whereby the brake arms may be separated from the retarding device to permit the lowering of the load, said mechanism including means whereby the speed may be 25 controlled manually and means whereby the retarding device may be placed out of commission to permit the jack to be lowered by hand.

The invention further consists in certain 30 novel features of construction and arrangement of parts which will be understood readily by reference to the description of the drawings and to the claims to be hereinafter given.

35 For the purpose of illustrating the invention, one preferred form thereof is illustrated in the drawings, this form having been found to give satisfactory and reliable results although it is to be understood that the various instrumentalities of which the 40 invention consists can be variously arranged and organized and the invention is not limited to the precise arrangement and organization of these instrumentalities as herein 45 shown and described, except as required by the scope of the appended claims.

Of the drawings:

Figure 1 represents a vertical section of a 50 lifting jack embodying the principles of the present invention.

Fig. 2 represents an elevation of the removable plate carrying the operating mechanism, the operating shaft being shown in section.

Fig. 3 represents an elevation partly in section, of the brake wheel and devices co-acting therewith.

Fig. 4 represents a horizontal section on line 4, 4, on Figs. 2 and 3.

Fig. 5 represents a vertical section on line 5, 5, on Fig. 4.

Fig. 6 represents a vertical section showing the brake arms removed from the brake wheel.

Fig. 7 represents an elevation of the ratchet-carrying disk, and

Fig. 8 represents an edge view of the brake wheel.

Similar characters indicate like parts throughout the several figures of the drawings.

In the drawings, 10 represents a suitable base supporting a stationary standard 11 over the outer periphery of which is fitted a movable sleeve 12, to the upper end of which is threaded a cap 13.

In the upper end of the standard 11 is mounted a nut 14 to which is threaded a lifting screw 15 having splined to its upper reduced end a bevel gear 16 with which meshes a bevel gear 17 formed upon or secured to a revoluble shaft or spindle 18, the outer end of which is provided with a suitable operating mechanism 19 of any well-known construction.

Between the upper face of the bevel gear 16 and the inner face of the cap 13 are two annular plates 20, 21, between which are interposed a plurality of anti-friction members 22.

The movable member 12 is provided on one side with a flanged projection 24 having a removable plate 25 secured thereto by bolts 25^x.

The plate 25 is provided with a bearing 26 for the spindle or shaft 18 and secured to the shaft 18 is a gear 29.

Beneath the gear wheel 29 is a revoluble shaft 35 having secured thereto a pinion 36 meshing with said gear 29 and driven thereby when the movable member 12 of the jack is moved in either direction.

The shaft 35 has also secured thereto a worm wheel 37 which meshes with a worm 38 revoluble in bearings 39 in the bracket 40 secured to the inner face of the removable plate 25 by screws 40^x.

On the reduced end 41 of the worm 38

is mounted a brake disk 42 with the periphery of which coacts two brake members 43 pivoted at 44 to the bracket 40.

5 The lower end of each brake member 43 is provided with a recess 45 in which is positioned one end of a helical spring 46 the opposite ends of said springs being disposed in the recesses 47 and 48 in the removable plate 25 and bracket 40.

10 Each brake member 43 is provided with a projection 50 which is preferably a roller as shown in the drawings.

15 Mounted in the bracket 40 and aligned with the worm 38 is an oscillating shaft 51 having secured to its outer end an actuator 52 and at its inner end a cam disk 53 having in the periphery thereof a depression 54 in which said projection 50 is adapted to be positioned under normal conditions.

20 The depressions 54 are sufficiently deep to permit the brake members 43 to be forced into contact with the brake wheel 42 which is loosely mounted on the reduced end 41 of the worm 38.

25 In other words, the projections 50 are not in contact normally with the cam disk 53 as shown in Fig. 3.

30 When, however, the cam disk 53 is moved in the direction of arrow *a* on Fig. 3, the gradually inclined cam throw 55 will come into contact with the projections 50 and move the brake members 43 against the tension of the springs from contact with the brake wheel 42.

35 Owing to the inclination of said cam throws 55, the movement of these members 43 from the brake disk 42 may be varied at will.

40 When it is desired to lower the jack by hand, the cam disk 53 is moved in the opposite direction to that indicated by the arrow *a* on Fig. 3 and the cam throw 56 will move the projections 50 outwardly until they rest upon the peripheral surface 57 which is a greater distance from the axis of the oscillating shaft than the peripheral surface 57 at the outer end of the cam throws 55.

45 Each brake arm 43 is provided on its inner face with a curved spring member 58 secured thereto with its free end resting in a depression 59 said members 58 thereby forming bridges which with the inner curved faces of the members 43 form a continuous surface with which coact the pivoted shoes 60 on the brake wheel 42.

50 When the brake wheel 42 is moved in the direction of the arrow *b* on Fig. 6 of the drawings, the brake shoes 60 will move outwardly about their pivots 61 and create sufficient friction on the brake members 43 and bridges 58 to retard the speed of rotation of the worm 38 and consequently regulate the lowering of the movable member 12 of the jack.

55 Each shoe 60 has a projection 62 adapted

to coact with a shoulder 63 on the brake disk 42 to limit the outward movement of the shoes 60 so that when the brake members 43 are in the position indicated in Fig. 6 of the drawings the shoes will not contact 70 with said brake members 43. This only occurs however when it is desired to operate the jack without permitting it to lower under its load.

Secured to and revoluble with the reduced 75 end 64 of the worm 38 is a disk 65 having mounted thereon a plurality of pawls 66 pivoted at 67 and adapted when the disk 65 is rotated in the direction of the arrow *b* on Fig. 6 of the drawings to engage with the 80 teeth of the ratchet wheel 68 keyed to and revoluble with the hub of the brake wheel 42, loosely mounted upon the reduced end 41 of the worm 38.

The worm 38 is rotatable in either direction when the load is being lifted or when it is being lowered and consequently the disk 65 is rotatable in either direction.

The pawls 66 are rotatable with the disk 65 and are preferably positioned in the recess in the brake wheel 42 as shown in Fig. 4 of the drawings.

When the jack is being raised, the pawls 66 will ride over the teeth of the ratchet 68 and impart no movement to the brake wheel 95 42 but when it is desired to lower the load under its own weight, the disk 65 will be moved in the opposite direction and the pawls 66 becoming engaged with the teeth of the ratchet 68 will cause the brake wheel 100 42 to be rotated therewith whenever the brake members 43 are moved by the cam disk 53 from contact with the brake wheel 42.

As the worm 38 rotates and causes the rotation of the brake wheel 42, the shoes 60 105 will move outwardly into contact with the inner surfaces of the brake arms 43 and the bridges 58 and retard the speed so that any excessive speed of lowering will be prevented.

The degree of retarding may be varied by manipulating the actuator 52.

To retain the load in elevated position the cam disk 53 is in the position indicated in Fig. 3 of the drawings and at this time the 115 brake members 43 will grip upon the brake wheel 42 sufficiently to prevent its rotation and owing to the engagement of the pawls 66 with the ratchet wheel 68 keyed to said brake wheel the disk 65 will also be prevented from rotating.

Owing to this disk 65 being locked from rotation, the worm 38 cannot be rotated and therefore there can be no lowering of the load until the brake members 43 are moved 125 from contact with the brake wheel 42.

This makes a simple and effective device for retarding the lowering of high speed lifting jacks.

It is believed that the operation and many 130

advantages of the present invention will readily be understood without further description.

Having thus described my invention, I 5 claim—

1. The combination with a lifting jack having a worm shaft adapted to be driven in either direction; a brake wheel loosely mounted on said worm shaft; a member 10 revolute with said worm shaft; a one-way driving connection between said brake wheel and said member; and a braking member adapted to coact with said wheel.

2. The combination with a lifting jack 15 having a worm shaft adapted to be driven in either direction; a brake wheel loosely mounted on said worm shaft; a member revolute with said worm shaft; a one-way driving connection between said brake wheel 20 and said member; a braking member adapted to coact with said wheel; and a cam member alined with said worm shaft for separating said braking member from the brake wheel.

25 3. The combination with a lifting jack having a worm shaft adapted to be driven in either direction; a brake wheel loosely mounted on said worm shaft; a member revolute with said worm shaft; a one-way 30 driving connection between said brake wheel and said member; a braking member adapted to coact with said wheel; and a cam member alined with said worm shaft for separating said braking member from the brake 35 wheel, said cam wheel being provided with two cam throws one of which is adapted to move the braking member a short distance while the other is adapted to move said braking member a much longer distance.

40 4. The combination with a lifting jack having a worm shaft adapted to be driven in either direction; a brake wheel loosely mounted on said worm shaft; a member revolute with said worm shaft; a one-way 45 driving connection between said brake wheel and said member; a braking member adapted to coact with said wheel; a stud projecting from said braking member; and a cam member alined with said worm shaft and 50 provided with a gradually inclined throw adapted to coact with said stud when rotated in one direction.

5. The combination with a lifting jack 55 having a worm shaft adapted to be driven in either direction; a brake wheel loosely mounted on said worm shaft; a member revolute with said worm shaft; a one-way driving connection between said brake wheel and said member; a braking member adapted to coact with said wheel; a stud projecting from said braking member; a cam member alined with said worm shaft and provided with a gradually inclined throw adapted to coact with said stud when rotated 60 in one direction; and a steeply inclined 65

throw adapted to coact with said stud when moved in the opposite direction.

6. The combination of a worm shaft adapted to be driven in either direction; a brake wheel loosely mounted on said worm 70 shaft; a member revolute with said worm shaft; a one-way driving connection between said brake wheel and said member; a braking member adapted to coact with said wheel; a stud projecting from said braking 75 member; a cam member alined with said worm shaft and provided with a gradually inclined throw adapted to coact with said stud when rotated in one direction; and a steeply inclined throw adapted to coact with 80 said stud when moved in the opposite direction, said steeply inclined throw terminating in a portion concentric to the axis of the worm shaft and at a greater distance from said axis than the outer end of said gradually inclined throw.

7. The combination with a lifting jack having a worm shaft adapted to be driven in either direction; a brake wheel loosely mounted on said worm shaft; means on said 90 worm shaft adapted to rotate said brake wheel in one direction only and that during the lowering of the load; a braking member normally coacting with said wheel; and means for moving said braking member from 95 contact with said wheel.

8. The combination with a lifting jack having a worm shaft adapted to be driven in either direction; a brake wheel loosely mounted on said worm shaft; means on said 100 worm shaft adapted to rotate said brake wheel in one direction only and that during the lowering of the load; a pivoted braking member normally coacting with said wheel; and means for moving said braking member 105 about its pivot from contact with said wheel.

9. The combination with a lifting jack having a worm shaft adapted to be driven in either direction; a brake wheel loosely mounted on said worm shaft; means on said 110 worm shaft adapted to rotate said brake wheel in one direction only and that during the lowering of the load; a braking member normally coacting with said wheel; and cam mechanism for moving said braking 115 member from contact with said wheel.

10. The combination with a lifting jack having a worm shaft adapted to be driven in either direction; a brake wheel loosely mounted on said worm shaft; means on said 120 worm shaft adapted to rotate said brake wheel in one direction only and that during the lowering of the load; a braking member normally coacting with said wheel; and an oscillating member adapted when moved in 125 one direction to move said braking member gradually from said wheel and when moved in the opposite direction to move said braking member a greater distance from said wheel.

11. The combination with a lifting jack having a worm shaft adapted to be driven in either direction; a brake wheel loosely mounted on said worm shaft; means on said worm shaft adapted to rotate said brake wheel in one direction only and that during the lowering of the load; a braking member normally coacting with said wheel; and an oscillating member adapted when moved in one direction to move said braking member gradually from said wheel and when moved in the opposite direction to move said braking member a greater distance from said wheel and retain it in its separated position.
12. The combination with a lifting jack having a worm shaft adapted to be driven in either direction; a brake wheel loosely mounted on said worm shaft; a ratchet secured thereto; a disk revoluble with said worm shaft; pawls carried by said disk and coacting with said ratchet; a braking member normally contacting with said wheel; and means for separating said braking member from said wheel.
13. The combination with a lifting jack having a worm shaft adapted to be driven in either direction; a speed retarding device loosely mounted on said worm shaft; and means on said worm shaft for rotating said retarding device in one direction only and that during the lowering of the load.
14. The combination with a lifting jack having a worm shaft adapted to be driven in either direction; a speed retarding device loosely mounted on said worm shaft and including a plurality of peripheral shoes movable outwardly during the rotation of said retarding device; and means on said worm shaft for rotating said retarding device in one direction only and that during the lowering of the load.
15. The combination with a lifting jack having a worm shaft adapted to be driven in either direction; a speed retarding device loosely mounted on said worm shaft and including a plurality of peripheral shoes movable outwardly during the rotation of said retarding device; means on said worm shaft for rotating said retarding device in one direction only and that during the lowering of the load; and braking members normally coacting with said retarding device and adapted to be removed from contact therewith to permit said shoes to move outwardly into frictional contact with said braking members.

WALTER E. LOMBARD.
